CRUMB TRAY

Richard B. Lawrence, Detroit, Mich.

Application January 7, 1949, Serial No. 69,744

3 Claims. (Cl. 65—20)

1

This invention relates to tableware and more particularly to an improved crumb tray with scraper.

One of the objects of the present invention is to provide an improved crumb tray with scraper, which is convenient in use and which eliminates functional disadvantages of prior constructions.

Another object of the invention is to provide an improved crumb tray and a scraper therefor, each of which can be made from a single piece of sheet material by a single stamping operation.

A further object of the invention is to provide an improved crumb tray having its various functional portions properly positioned for convenient holding and use, and yet in such relative positions as to ensure smooth flow of the material during the forming stage of the stamping operation, as well as easy trimming after forming is completed.

A still further object of the invention is to provide an improved crumb tray made from a single piece of sheet material by a single stamping operation and provided with a handle which while being convenient in use does not stick out for such a distance as to present danger of accidental knocking off the tray from the table and does not occupy too much space when the crumb tray is put away into a drawer.

A still further object of the invention is to provide an improved crumb tray which does not rock and stands firmly if left on the table.

A still further object of the invention is to provide an improved crumb tray which is compact in packing, and which when packed for shipment in large numbers will stack up one into another.

A still further object of the invention is to provide an improved crumb tray, which, while satisfying the above specified functional requirements, is of a pleasing appearance and is adapted to receive well various surface finishes and ornamentations suitable for an article of silverware or tableware.

Fig. 1 is a perspective view showing an improved crumb tray with scraper embodying the present invention.

Fig. 2 is a top view of the crumb tray with scraper shown in Fig. 1.

Fig. 3 is a sectional view taken in the direction of the arrows on the section plane passing through the line 3—3 of Fig. 2.

Other objects of this invention will appear in the following description and appended claims, reference being had to the accompanying draw-

2

ings forming a part of this specification, wherein like reference characters designate corresponding parts in the several views.

In describing the crumb tray embodying the present invention, the table-contacting edge thereof is considered for the purpose of description as the front, and the handle as the rear of the tray. The terms "upper" and "lower" are used with reference to tray portions correspondingly disposed when the tray rests flat on a straight horizontal surface.

In the drawing there is shown, by way of example, an improved crumb tray with scraper, embodying the present invention. Referring to the drawing, the crumb tray generally designated therein by the character C comprises a crumb-receiving pocket of an elongated shape and extending with its longer dimension transversely to the direction of sweeping into said pocket.

The pocket has a flat bottom 10 of an elongated shape surrounded with vertically extending, upwardly diverging walls. The front edge 11 of the bottom 10 is substantially straight and it merges into the front wall 12 of the pocket, while the rear edge 13 is of an arcuate form and merges with the back wall 14. The end edges 15, 15 of the bottom are also arcuate and they merge into the end walls 16, 16. I prefer to use 10½ inch radius for the rear edge 13 and ½ inch radius for the end edges 15, 15. The curvature at the corners at the places of juncture of the bottom and the walls is approximately ¼ of an inch. However, other values for the above radii may be used to suit other conditions.

The rear wall 14 of the crumb-receiving pocket is higher than the front wall 11. Along the upper edge 17 of said rear wall 14 there is provided a horizontally extending flange 18 having an upstanding flange 19 provided along its rear and end edges. The flange 18 may also be termed a handle flange, since it is provided, in addition to other reasons, also to form a handle for the tray.

In front of the wall 12 there is provided an inclined ramp 20 having a rear edge merging into the wall 12 and end walls 16, 16 of the pocket, while its front edge forms a straight edge or lip 21 lying in the plane of the bottom 10. I prefer to have the ramp 20 and the handle flange 18 to lie in approximately parallel planes. Side edges 22, 22 of the ramp converge toward the crumb-receiving pocket and merge with ramp flanges 23, 23. Each of the flanges 23 comes substantially to a point at the lip 21 and gradually increases in height rearwardly, so that its rear end merges into the end wall 16, handle flange 18 and vertical

flange 19. By virtue of such a construction a continuous upper edge is provided from the lip 21 around the entire tray. Said edge may form at the ramp flanges a pleasing curve, as indicated at 24. The flanges 23, 23 are upwardly diverging, each of said flanges forming on the outside of the pan an angle of approximately 60 degrees with the horizontal plane, or the plane of a table on which the crumb tray may be placed. In other words, downward continuation of the planes of said flanges 23, 23 form between themselves an included angle of approximately 60 degrees, said angle slightly decreasing toward the crumb-receiving pocket in order to effect a more gradual merging of the flanges 23, 23 with the handle flange 18.

A hole 25 is provided in the handle flange 18 for hanging the tray on a nail or hook on the wall as well as for suspending it in plating, if required.

I prefer to make the tray of such dimensions as to have its lip approximately 7 inches long, with the distance along the center line of the tray from the lip 21 to the flange 19 being approximately 6 inches; the length of the bottom crumb-receiving pocket may be also approximately 6 inches.

All of the above described elements of the tray construction merge smoothly and seamlessly into one another. Where they form an angle, it is preferable to have a radius at the vertex of such an angle of approximately one quarter of an inch. However, at the places of juncture of the ramp 20 and flanges 23, 23 such radius may be dispensed with and a much smaller radius such as one sixteenth of an inch may be used. By virtue of such a construction the tray may be made even from such materials as sheet steel in a single stamping operation, its forming and trimming being accomplished in a single stroke of the press.

The scraper S is also constructed to be made in a single stamping operation, and it comprises a flat body 30 having a straight lower edge 31 of the length equal or slightly smaller than the length of the crumb-receiving pocket of the tray C, thereby ensuring that the scraper will enter the tray and can be moved over the ramp and for some distance over the crumb-receiving pocket without interference at the flanges 23, 23. It is preferable to make the scraper approximately three inches high. The upper edge of the scraper is preferably curved and has a bead provided along it to strengthen the body 30 and to impart to the scraper a more pleasing appearance. A scraper of this construction affords a very comfortable and secure hold and is very convenient to use. A hole 33 may also be provided in the scraper at any suitable place. I prefer to provide such a hole at one side of the scraper.

By virtue of providing the above disclosed crumb tray and scraper therefor, object of the present invention and numerous additional advantages are attained.

I claim:

1. A crumb tray made by stamping from a single piece of sheet material, said tray including a crumb-receiving elongated pocket extending with its longer dimension transversely to the direction of sweeping into said pocket, said pocket having a flat bottom with well rounded ends and adapted to rest flat on a straight surface, walls surrounding said bottom and merging smoothly and seamlessly therewith, an inclined ramp merging smoothly and seamlessly with the front and side walls of said pocket and terminating in a table contacting lip, a horizontally extending flange provided along the back wall of said pocket and merging smoothly and seamlessly into said back wall and end walls of said pocket and adapted to be used as a handle for said tray, and inclined side flanges provided along the sides of said ramp and having front ends terminating at said lip and rear ends merging smoothly and seamlessly with the upper portion of the wall of said crumb-receiving pocket and also merging seamlessly with said horizontally extending flange.
2. A crumb tray as defined by the preceding claim 1, said side flanges coming to substantially a point at the lip of the ramp.
3. A crumb tray as defined by the preceding claim 1, said horizontally extending flange being turned up at its back and end edges to form an upstanding flange having ends merging seamlessly into the back ends of the ramp side flanges.

RICHARD B. LAWRENCE.
